ATTORNEY

UNITED STATES PATENT OFFICE.

THEODORE BAUMAN, OF MILWAUKEE, WISCONSIN.

SHOE FASTENER.

Application filed March 15, 1924. Serial No. 699,487.

To all whom it may concern:

Be it known that I, THEODORE BAUMAN, a citizen of the Republic of Switzerland, residing at Milwaukee, in the county of Milwaukee and State of Wisconsin, have invented new and useful Improvements in Shoe Fasteners, of which the following is a specification.

This invention relates to shoe fastening devices and has for an object the provision of means whereby a shoe may be quickly fastened and unfastened, and which will yield to the action of the foot and ankle when the shoe is worn, so that the shoe may be set snugly upon the foot without discomfort.

Another object of the invention is the provision of shoe fastening means which is simple in construction, reliable in use and which may be readily and securely attached to a shoe.

With the above and other objects in view, the invention further includes the following novel features and details of construction, to be hereinafter more fully described, illustrated in the accompanying drawings and pointed out in the appended claim.

In the drawings:—

Figure 1 is a perspective view looking at the front of a shoe with the invention applied, some of the fastening devices being open.

Figure 2 is an enlarged section on the line 2—2 of Figure 1.

Figure 3 is a detail perspective view of the permanent member of the fastening device.

Figure 4 is a similar view of the detachable member.

Referring to the drawings in detail where like characters of reference denote corresponding parts, the reference character 10 indicates a shoe, the upper of which is shown as separated after the manner of the ordinary laced shoe but it is of course obvious that the invention may be applied to different types of shoes. The invention which is designed for the purpose of providing a shoe fastening means, comprises an elastic loop 11 which is designed to connect the adjacent edges of the shoe upper and to be so attached to the shoe that it may be renewed when necessary. For this purpose there is secured along one edge of the upper

what will be hereinafter referred to as permanent attaching devices 12. These devices are provided with penetrating points 13 which are adapted to be passed through the upper and to have their extremities bent over or upset as shown at 14, whereby the devices will be securely and permanently held in place. These devices are provided with transversely disposed openings 15 having restricted entrance slots 16, so that the elastic band 11 may be inserted through these slots and retained within the openings 15 against accidental displacement.

The reference character 17 indicates what will be hereinafter termed detachable fastening devices, the latter being of hollow construction and provided upon their under faces with openings 18 which are substantially key-hole shaped. That is, these openings have an enlarged end and a restricted end, the former being adapted for the passage of headed studs 19, while the latter receive the shanks of these studs with the heads of the studs within the hollow detachable members. The elastic loops 11 are attached to the members 17 and for this purpose the said members are provided with restricted entrance slots 20 which communicate with the large end of the openings 18, so that the loops 11 may be removably inserted through the slots into these openings. The member 17 may thus be engaged over the headed studs 19 and the elastic loops will act to prevent accidental disengagement. The headed studs 19 may extend from plates 21, the latter having penetrating points 22 which are passed through the shoe upper and bent over or upset after the manner of the penetrating points 13.

It will be apparent from the foregoing description and accompanying drawings that the invention provides a simple, economical and easily manipulated fastening device for shoes, the character of the device being such that it may be readily renewed. In addition, the devices 12 and 17 may be of any suitable size and shape and may be made of any suitable attractive material so as to add to the attractiveness of the shoe as well as provide a convenient fastening means.

The invention is susceptible of various changes in its form, proportions and minor details of construction and the right is here-

in reserved to make such changes as properly fall within the scope of the appended claim.

Having described the invention what is claimed:

A shoe fastener of the character described comprising a plurality of permanent fastening devices secured to one side of a shoe upper and having their inner edges transversely disposed and providing a restricted entrance slot, detachably connected resilient loop members passing through the respective slots at one end, a plurality of hollow

detachable fastening devices having substantially key hole slots in the undersides thereof and receiving the opposite ends of the resilient loop members within a restricted entrance slot adjacent the enlarged portions of the key hole slot and a plurality of headed studs secured to the opposite sides of the shoe upper and adapted to receive the hollow detachable fastening devices thereon. 15 20

In testimony whereof I affix my signature.

THEODORE BAUMAN.
